UNITED STATES PATENT OFFICE.

JOHN PETERSON, OF QUINCY, MASSACHUSETTS.

CLASP FOR GARMENT-SUPPORTERS.

SPECIFICATION forming part of Letters Patent No. 580,293, dated April 6, 1897.

Application filed December 7, 1896. Serial No. 614,687. (No model.)

To all whom it may concern:

Be it known that I, JOHN PETERSON, a citizen of the United States, and a resident of Quincy, in the county of Norfolk and State 5 of Massachusetts, have invented new and useful Improvements in Clasps for Garment-Supporters, of which the following, taken in connection with the accompanying drawings, is a specification.

10 This invention relates to improvements in clasps for garment-supporters, and although particularly designed for use on suspenders for holding up drawers it may equally well be used as a stocking-supporter or supporter 15 for garments of any kind, as will hereinafter be more fully shown and described, reference being had to the accompanying drawings, wherein—

Figure 1 represents a front elevation of the 20 improved clasp, shown as attached to the upper edge of a garment. Fig. 2 represents a longitudinal section on the line 2 2, shown in Fig. 1. Fig. 3 represents a side elevation of the improved clasp, shown in its expanded 25 position. Figs. 4, 5, and 6 represent the sheet-metal blanks composing the improved clasp.

Similar letters refer to similar parts wherever they occur on the different parts of the drawings.

30 The improved clasp is made from two sheet-metal blanks A and B. (Shown, respectively, in Figs. 4 and 5.) The blank A has a circular, or nearly so, lower end A', having a serrated end portion A'', which is bent inwardly, as 35 shown in Figs. 2 and 3.

A³ A³ are side projections which are afterward bent or doubled over to serve as fulcra for the coiled spring C, interposed between the jaws of the clasp, as is common in de-

40 vices of this kind.

On said blank A above the portion A', which I term the "stationary" clamping-jaw, is a shank A⁴, having laterally-extended wings A⁵ A⁵, which are afterward bent or doubled 45 over the cord or strap D, that constitutes the garment-suspending strap, as usual. Above the wings A⁵ A⁵ the shank A⁴ has an extension A⁶, which is bent downwardly as an inclined protector. (Shown in Figs. 1, 2, and 3.) The

blank B has also a circular, or nearly so, 50 clamping-jaw B', provided with an inwardly-bent and serrated end B'', as shown. Said blank has side projections B³ B³, corresponding with the projections A³ A³ on the blank A and for a similar purpose. On the blank 55 B above the portion B', which I term the "movable" jaw, is a shank B⁴, which is afterward curved outwardly and below the protector A⁶ when the parts are assembled for use, as shown in Figs. 1, 2, and 3. Normally 60 the spring C holds the serrated jaws A' B' closed and holds them firmly in contact with opposite sides of the garment E, introduced between said jaws in the usual manner. (Represented in Figs. 1 and 2.)

65 For the purpose of more firmly holding the garment between the jaws I prefer to attach to the interior of the jaws A' B', above the serrated lips A'' B'', U-shaped serrated duplex clips f f, which are made from blanks 70 F (shown in Fig. 6) and afterward bent or doubled into the U-shaped form shown in Figs. 2 and 3 and preferably soldered or otherwise attached to the inside of the jaws A' B', as represented in Figs. 2 and 3.

75 The great advantage in this clasp over others is that the stationary jaw A' is provided with an upper extension A⁶, bent downward in an inclined position, so as to serve as a cover or protector for the upper end of the 80 shank B⁴ of the movable jaw, thus preventing garments in contact with the shank B⁴ from being caught or torn on such shank.

85 Another advantage is the arrangement on the inside of the jaws of additional serrated ledges f f, as hereinabove set forth and described.

What I wish to secure by Letters Patent and claim is—

1. A garment-supporting clasp, consisting 90 in combination, a pair of spring-pressed pivoted jaws A', B', an inclined protector A⁶ on the shank of the jaw A', a movable shank B⁴, arranged below such protector and auxiliary serrations f f, arranged on the interior of the 95 jaws A', B', above their main serrations A'', B'', substantially as and for the purpose set forth,

2. A garment-supporting clasp composed of stationary and movable serrated jaws pivoted together combined with auxiliary serrated plates *f* secured to the interior of said jaws above their main serrations A'', B'' substantially as and for the purpose set forth.

In testimony whereof I have signed my

name to this specification, in the presence of two subscribing witnesses, on this 27th day of November, A. D. 1896.

JOHN PETERSON.
